MINGTON, DELAWARE, A CORPORATION OF DELAWARE

NUMBERING MACHINE

Application filed February 17, 1928. Serial No. 254,929.

This invention relates to numbering machines, and particularly to machines for printing consecutive numbers on continuous lengths of material. While the invention is not restricted thereto, the present embodiment thereof has particular application to, and is described in connection with, the application of consecutive footage numbers to photographic film. For example, the illustrated machine may be used in the production of ink-numbered film of the type described and claimed in the application of John H. Clewell and Frank H. McCormick, Serial No. 269,594, filed April 12, 1928, and entitled Numbered motion picture film.

One object of the invention is to provide a machine for placing any desired indicia on continuous lengths of material as they are passed through the machine. Another object is to provide a machine for printing consecutive indicia, as footage numbers, on continuous lengths of photographic film, as cinematographic film. To these ends, and also to improve generally upon machines of the character indicated, this invention consists in the various matters hereinafter described and claimed.

In the accompanying drawings, Figure 1 is an elevational view of a machine embodying the invention; Figure 2 is a vertical section taken substantially on the line 2, 2 of Figure 1; Figure 3 is a view, to an enlarged scale, taken substantially on the line 3, 3 of Figure 2, showing the mechanism whereby the numbering device proper is actuated; Figure 4 is a view looking substantially in the direction of the arrow 4 in Figure 1, and showing the mechanism for inking the type of the numbering device proper; Figure 5 is a broken out face view of a section of film as numbered by the machine, the numbers on the film being dotted in to indicate that they are viewed through the film, they having been impressed on the lower side of the film as the film is passed through the machine; and Figure 6 is a conventional elementary skeleton view of the machine assembled and mounted with a perforating

machine to receive the film therefrom and be driven thereby.

Referring now to the drawings, the illustrated machine in general comprises a film driving and supporting wheel 1, a rotatable member 2 carrying, rotatable therewith, the printing mechanism proper 3, an inking mechanism, designated generally as 4, for inking the type of the printing mechanism 3, and a type-cleaning device, indicated as a brush 5, for cleaning the type of the printing mechanism 3 as the printing mechanism is carried past the brush during the rotation of the member 2. Cooperative with the printing mechanism 3, is a cam-actuated mechanism, designated generally as 6 (Fig. 3), for actuating the printing mechanism during rotation of the same with the carrier 2, the cam-operated mechanism 6 being controlled by the cam 7. The machine also embodies guiding devices 8 and 9 for leading the film F to, and receiving it from, the driving wheel 1.

Conveniently, the machine is assembled with a perforator, to number the film immediately after the making of the perforations, and to be driven by the perforator. Such an assembly is shown in Figure 6. As there shown, the driving wheel 1 is driven from the perforator by the driver 10 on a continuously rotating shaft of the perforator, the chain 11 and the sprocket 12 driving the film-moving wheel 1. Also the member 2 is driven from sprocket 12 by the gears 13 and 14 (Fig. 2). The assembly of Figure 6 is shown as also embodying a roll R of film F, a perforating mechanism P, idlers I (floating) and I', which, together with the idler 9, form a loop in the film which gives the ink time to dry before being wound up on the wind-up roll W. The wind-up roll is driven, by a suitable slipping clutch connection, from the shaft 10 of the perforator.

In brief, the operation is as follows. The film F is fed from the storage roll R through the perforator P, where it is perforated, and thence through the idler assembly 8, and between the members 1 and 2, and through the idler mechanism 9, and over idlers I and I' to the wind-up roll W, the wind-up roll W

being driven from the perforator. The members 1 and 2 are driven from the perforator, as before described, and the film is carried forward by the member 1. In passing between the members 1 and 2, the printing mechanism rolls in contact with the film and prints the numbers consecutively thereon, a number being printed once for each revolution of the member 2 (and 1). The parts are so proportioned, and the gearing such, that the speed of the film being carried by the wheel 1 is the same as the speed of the numbers of the printing mechanism in their circumferential travel with the member 2, whereby there is no speed differential between the film and the numbers on the printing mechanism, both having the same linear velocity, whereby any blurring of the printing is obviated. For printing footage numbers on film, the parts are, of course, so proportioned that a number will be printed on the film at each foot. During each revolution of the carrier 2, the number displayed by the printing device is advanced one unit, whereby immediately consecutive numbers are printed on the film one foot apart. The carrier 2 rotates anti-clockwise in Figure 1 (the driver 1 rotating clockwise), whereby the counter mechanism is, in each revolution, carried past the cleaning brush 5 and then past the inking mechanism 4, where a fresh supply of ink is applied to the counter. Preferably, and as here shown, the parts are so arranged that the counter number is changed in the travel of the counter from a point in register with the brush, to the inking roll. Any suitable ink may be used, it preferably comprising a dye or pigment, a solvent for the film, and an adhesive, say shellac, to give the ink suitable adherence and proper body. Preferably, but not necessarily, the ink may be of the general type described and claimed in the application of John H. Clewell Serial No. 269,595, filed April 12, 1928, and entitled Ink for cellulose ester bodies.

Proceeding now to a detailed description of the machine. The machine comprises the supports 15 and 16 carried at their lower ends in the base 17 and supporting at their upper ends the fixed cross member 18, which carries the wheel 1 rotatably mounted with respect thereto. The supports carry, slidably mounted thereon, the carriage member 10 which supports, rotatably mounted thereon, the carrier 2. The carriage 19 is maintained in position with respect to the top member 18 by means of the expansion springs 20, adjustable by means of collars 21. With this construction, it is evident that the wheel 2, and hence the printing mechanism 3, is urged toward the wheel 1 with a yielding pressure, readily adjustable to provide for proper contact of the type of the printing mechanism with the film.

• 65 The film-driving wheel 1 is carried upon

a shaft 22 for rotation therewith, the shaft 22 being mounted in bearings 23 for rotation with respect to the top member 18 and carrying the assembly 24 fixed on the shaft 22 for rotation therewith. The assembly 24 70 comprises the sprocket 12, previously described as receiving its drive from, for example, any suitable motor mechanism, as a perforator P, and also comprises the gear 13, previously mentioned, which drives the 75 carrier 2 of the counter. The wheel 1 and the assembly 24 are each keyed to the shaft 22 by pin and slot constructions 25 and 26, the member 1 abutting the collar 27 being held by the knurled nut 28, while the assembly 24 is similarly held by the cone 29 and the nuts 30.

The carrier 2 for the printing mechanism, and the gear 14, are carried upon the shaft 31 substantially as the members 1 and 24 are carried on the shaft 22 (see Fig. 2), while the shaft 31 is mounted in the carriage 19 substantially as the shaft 22 is mounted in the top member 18.

The carrier 2 comprises a hub 32 with a web 33, and presents the slot 34 in which is received the pin 35 which connects the carrier 2 with the shaft 31. The hub 32 is provided with lugs 36 to which is bolted the web 33 and through which are slidably passed rods 37, each of which presents at its upper end a bearing block 38, these blocks being connected by a cross pin 39. To this cross pin are connected levers 40, one adjacent each end of the pin, for actuating the printing mechanism proper, or counter, as will be hereinafter described.

At their lower ends the pins 35 support a cam-roller-support 41. This support presents the lugs 42 and the support 43 for the cam roller 44. To the lugs 42 are attached contractile springs 45 connected at their other ends to the web 33 of the carrier 2. These springs urge the cam roller 44 into contact with its cam 46. The cam 46 is stationarily mounted upon the carriage 19.

Upon the web 33 and encircling the hub 32 is carried, fast with the web, a plate 47 provided at its upper end with arms 48. Carried by these arms is an axle pin 49 upon which are mounted the various type disks of the printing mechanism proper, or counter, 3. The screw 50, which serves to attach the plate 47 to the web, also attaches thereto, at the opposite side thereof, a guide plate 51 115 serving as a steadyng guide for the cam-roller-support 41, it resting between lugs 52 thereon.

The counter may be of any suitable type, as one of the general type of counter illustrated somewhat conventionally herein (no claim being herein made for the specific type of counter illustrated). The illustrated counter comprises a series of number discs 53, each carrying raised type numbers 53a in 130

sequence from 0 to 9 axially and rotatably mounted upon the axle pin 49. As will be understood by those skilled in the art of counters, each of these discs is provided with a ratchet wheel 54 moved by a spring pressed pawl 55, the series of pawls being independently oscillatable upon a bar 56. As will be further understood by those skilled in the counter art, the arrangement is, as usual, such that the units pawl is operated to move its wheel one unit at each oscillation, the tens disc moved one unit at each tenth oscillation of its pawl, and so on, this action being accomplished, as is usual, by providing each ratchet with a tooth depression of a different depth from the tooth depressions of any of the other ratchets, with the tooth depressions of the different ratchets progressively differing in depth from one disk to the next.

Returning to the levers 40, herebefore mentioned, these are fulcrumed on the axle pin 49, and carried between them and fast connected thereto, is the pawl bar 56. The levers have a slotted connection 57 with the before-mentioned cross pin 39. With this construction, when the carrier 2 is rotated, and the cam roller 44 follows the surface of the stationary cam 46, the member 41 is moved downward (as in Fig. 2) by the cam and is drawn upward by the springs 45. This motion of the cam-roller support causes a corresponding motion of the cross pin 39, and an oscillation of the levers 40 about the fulcrum 49, thus causing a corresponding motion of the pawl bar 56, and, hence, actuation of the pawls to move the type discs of the counter, the units wheel being advanced one type tooth at each oscillation of the pawl bar and the other discs being operated once every tenth, once every hundredth oscillation, and so on, due to the pawl teeth of successively different depth in the ratchets of the type discs. As will be seen from Figure 2, the arrangement is such that the motion of the cam roller carrier which causes actuation of the type discs is the downward (Figure 2) motion brought about by the cam, whereas the springs 45 serve merely to pull the cam-roller-support upward and cause the pawls to move anti-clockwise (in Figure 2). Thus the motion of the type discs is positive, the cam serving this purpose. As will be evident by reference to Figure 3, wherein the cam 46 is shown by phantom lines, there will be one operating oscillation of the levers 40 for each revolution of the carrier 2, and the changing of the number displayed by the counter will take place during the travel of the counter from a point in register with the type cleaner 5, to the inking roll 4, as herebefore described. As shown in Figures 1 and 3, the counter assembly is approximately "barrel shape" to give proper rolling con-

tact with the wheel 1, its radius of rotation being the same as that of the film on the wheel 1, and the speed of the type and film being the same. If desired, and as here shown, the cross pin 49, which carries the counter discs, may also carry additional discs 53^a for other desired indicia, these discs being hand set and locked in any suitable manner, as will be understood by those skilled in the art of hand-set disc printing devices.

Now to describe the inking mechanism heretofore generally designated as 4. The mechanism comprises the trough 59, suitably supported on the carriage 19, fed from the reservoir 60 by way of the pipe 61, and having the overflow pipe 62 by which the ink is maintained at constant level in the trough. A knurled ink-carrying roller 63 is mounted in the trough 59 to dip into the ink therein, and a felt inking pad 64 is mounted in the trough for contact with the roller 63 to aid in the spreading of the ink upon the roller. As shown in Figure 1, the pad 64 is carried, vertically slideable, in a support 65, and is spring pressed, by the spring 66, into contact with the roller 63. The roller 63 is driven from the previously mentioned shaft 31 by way of the sprocket 67 (Figure 2), the sprocket 68, on the shaft 69 of the roller (Figure 4), and a connecting chain 68^a. Mounted between extensions 70 of the sides of the trough, is the contact inking roller 71 for immediate contact with the type of the counter. The roller 71 has its axle 72 mounted in arcuate slots 73 in the extensions 70, these slots being concentric with the shaft 69 of the roller 63, and so located, as shown in Figure 1, that the tendency of the roller 71 is to drop towards the counter carrier 2. The position of the roller 71 is adjusted by the arms 74 pivoted at 75 and contacting the ends of the shaft 72 of the roller 71. These arms are held in adjusted position by any suitable means, as frictional contact with the pivots 75 and the extensions 70. By adjustment of the arms the exact positioning of the roller 71 to give it desired contact with the type is readily made. The roller 71 is driven by contact with the roller 63. It will be understood that the gear ratios, and proportions of the parts are such, that the roller 71 has the same surface speed as the type of the counter. The felt scraper 76 is carried on the trough for removal of excess ink from the roller 63.

The amount of ink carried by the roller 63 to the inking roll 71 can be reduced and regulated by grooving or knurling the surface of 63. The wiper 76 does not leave enough ink on 63 to fill up the grooves. The small amount of ink remaining spreads by capillary attraction over the high spots (the edges of the grooves) and the wheel 71 picks up ink only from the high spots of 63.

with which it makes contact. The area and number of these high spots can be regulated to suit the ink used, the maximum amount of ink being carried by a smooth faced wheel. The surface of wheel 71 is preferably porous (felt for instance) to facilitate the even distribution of ink picked up from the high spots of wheel 63.

Referring now to the mechanism herefore designated generally as 8 and 9, for guiding the film to and from the film-driving wheel 1. These mechanisms are alike, except for being lefts and rights, and a description of one will, therefore, suffice for both. The film-guiding wheel, as 8, is rotatably mounted upon a bracket 77 on the head or top member 18 and is desirably located in the plane of the wheel 1, whereby the film is desirably given a straight line delivery to the wheel 1 (and has a straight line discharge therefrom to the wheel 9). Also, carried by the bracket 77, concentric with the roller 8, is a swinging arm 78. The bracket 77 has an extension 79 and connecting this extension and the lever 78 is a contractile spring 80. As will be understood by those skilled in the art, and by reference to Figure 1, the spring 80 serves to hold the outer end of the lever 78 toward the wheel 1, or away therefrom, as shown by dotted lines, according to whether the lever is swung to carry the spring to the left or the right of the axis of oscillation of the lever 78. The retraction of the arm 78 is limited by a pin-and-slot construction 81 between the bracket 77 and the arm. The lever 78 carries at its outer end, in the plane of the wheel 1, a pressure roller 82 for forcing the film into contact with the wheel 1. The roller 8 has flanges 83 at each side thereof for the retention of the film, while the driving wheel 1 has sprocket teeth 84 spaced for meshing with standard perforations of the film, as perforated preferably by the illustrated perforating machine.

The bracket 77^a, which carries the idler 9, also conveniently carries the idler 1', as shown in Figure 1. As shown in Figure 2, the idler 1' is provided with upstanding tracks 85 on which the film may immediately rest. Such other film wheels as may be desired may also be provided with similar tracks, as indicated, for example, at 8^a and 9^a, by dotted lines.

While, in Figure 1, the roller 82^a is shown as swung away from the wheel 1, in order to better illustrate the positions which the rollers 82 and 82^a may occupy, it will be understood that when the machine is in operation the roller 82^a, as well as the roller 82, is swung into position to apply pressure to the film, thus to hold the film firmly on the wheel 1 during printing. When film 65 is to be threaded through the machine, the

roller 82, as well as the roller 82^a, is swung into retracted position.

In Figure 5, is illustrated a film as numbered by the present machine. In this figure, the numbers are dotted, thereby to indicate that they are viewed through the film, since the present machine places the numbers on the lower side of the film as the film is fed through the machine. In the figure, the film has been turned end for end, as received from the machine, in order that the numbers may read right side up. As illustrated, the machine prints the numbers on the extreme margin of the film between the perforations and the edge of the film. The film may, of course, be fed to the machine to print the numbers either upon the emulsion side or upon the back, as may be desired.

Returning to the carriage 19 which is urged toward the head 18 by the lower (in Figure 1) springs 20 (the movement being somewhat buffered by the upper springs) in order to press the numbers 53^a into proper contact with the film, it will be understood that the teeth of the gears 13 and 14 are of such height, and mesh with such clearance, that the drive is properly maintained despite the "go and come" movement of the carriage during operation of the machine, this motion being but slight. In this way, the gearing does not interfere with the proper pressing of the type against the film, nor does the "go and come" movement of the carriage interfere with the drive. If desired, and as illustrated in Figure 2, the gear 14 may be split through in the plane of the gear, that is made in two circular halves, and these connected by bolts passing through over-diameter holes in one of the halves. With this arrangement, one-half may be rotated slightly with respect to the other to, in practical effect, increase the width of the teeth circumferentially; and similarly with the gear 12.

We claim:

1. In a numbering machine, a supporting frame, a rotating drum-like element carried thereby, means for rotating such element, a numbering mechanism carried by said element and including a shaft arranged in chord position on said element and a ratcheted number disc rotatable on said shaft, and means for rotating said disc upon rotation of said element; such means comprising a cam-follower carrier radially slideable upon said element, a lever fulcrumed upon said shaft and pivotally connected to said carrier, a pawl pivotally connected with said lever and engaging the ratchet of said disc, a cam-follower carried by said carrier, and a cam stationarily carried by said frame and in engagement with said follower, said cam being contoured to slide the carrier during rotation of the element 115 120 125 130

thereby to actuate the lever, pawl and number disc.

2. In a numbering machine, a supporting frame, a rotating numbering-device carrier supported by said frame, a numbering device carried by said carrier for rotation therewith and having type, a type-cleaning device and a type-inking device carried by said frame in position to be contacted by the type of the numbering device in the circumferential travel of such device with the rotating carrier, said cleaning device and said inking device being spaced along the path of travel of the numbering device, means to drive the carrier in a direction to carry the numbering device from the cleaning device to the inking device, and means for changing the displayed numbers of the numbering device during travel from the cleaning device to the inking device.

In testimony whereof we affix our signatures.

OLIVER E. CONKLIN.
